ABSTRACT: An expanded foam polystyrene carafe including a body having a pouring spout. A lid is frictionally seated for rotation within the open end of the body and has a nose formed with a groove on the underside thereof. The groove provides a pouring passage when the lid nose is aligned with the pitcher pouring spout. Rotation of the lid so that the lid nose and pouring spout are angularly displaced is operative to seal or close the pouring spout.

INVENTOR
COLON M. STEPHENSON

MECHANICAL CARAFE

The present invention relates to carafes and more particularly to a carafe of the type used in public establishments such as hotels, hospitals and the like.

By the present invention it is proposed to provide a carafe which is made of a lightweight, insulating material so that the contents of the container may retain the desired temperature for an extended period.

It is another object of the invention to provide a carafe taken in conjunction with the foregoing proposed carafe structure wherein the material is economical, nonabsorptive and capable of withstanding sterilization temperatures.

It is still another object to provide a carafe with a cover and pouring spout constructed and arranged so that upon rotation of the cover relative to the pouring spout the cover is operative to selectively open or close the pour opening.

It is still a further object to provide a new and improved pouring spout arrangement which serves in the nature of a strainer during pouring of the liquid contents and thereby retains ice or other solid objects within the container.

It is another object to provide a carafe which is constructed so as to permit nesting of a plurality of carafes within each other for storing and in a manner permitting easy separation thereof.

Other objects and features will appear from the specification and drawings in which:

FIG. 1 is an elevational view of the carafe embodying the structure of the present invention with cover shown in an exploded position spaced from the carafe body;

FIG. 2 is a longitudinal vertical cross-sectional view through the carafe body and cover seated thereon;

FIG. 3 is a top plan view of the carafe;

FIG. 4 is a fragmentary cross-sectional view through a pair of nested or stacked carafes; and

FIG. 5 is a fragmentary top plan view of the container showing the cover in a full open position to permit pouring of the contents through the pour spout and showing in phantom lines the position of the cover to close off and prevent pouring of the contents through the pour spout.

Referring now to the drawings wherein similar reference numerals are used to indicate similar parts thereof, there is illustrated a carafe 10 embodying the structure of the present invention. The carafe 10 comprises a container body 11 and a removable cover or lid 12. The body 11 and cover 12 may be made from the same materials, preferably a plastic material capable of providing insulation. One such plastic material showing the required characteristics is an expanded foam polystyrene. The expanded foam polystyrene is particularly suitable because of the adaptability to molding techniques by which the body 11 and cover 12 may be formed. When molded the expanded polystyrene forms a substantially smooth and cell free exterior surface which is moisture resistant so that the body 11 and cover 12 do not absorb the liquid contents. Moreover, the expanded foam polystyrene has the additional advantage of low costs, both for the raw material itself and for the mold structures for fabricating the carafe. Also, the polystyrene is not subject to fungus attack or bacterial growth which renders the material particularly suitable for hospital use. The light weight and shock resistance of the polystyrene greatly enhance its use. A further factor is the ability of the foam polystyrene to withstand heat at least as high as that required for sterilization so that the carafe may be reused.

As shown, the body 11 is molded as a one-piece structure generally in the form of a pitcher having an open end 13 and a bottom 14. The body or pitcher 11 is formed in upper section 16 and a lower section 17 to provide an interior stacking or nesting rim 18 and an exterior stacking or nesting rim 19. The wall thickness of each of the sections 16 and 17 may be the same. The interior walls of the sections 16 and 17 are substantially smooth, while the exterior walls are formed with a plu-

rality of horizontal bands 21 of substantially equal width which decrease in diameter from the top to the bottom.

The nesting rims 18 and 19, as shown in FIG. 4 are located to prevent the lower section 17 of one container from wedging into the upper sections 16 of a container into which it may be stacked or nested. Moreover, the horizontal bands 21 on the exterior wall of the lower section 17 of the container nested within the upper section 16 maintain a slight separation or spacing between the adjacent walls and thereby the tight wedging usually associated with stacking is minimized. In this manner the carafes may be easily separated.

An integral handle 22 of generally T-shaped cross section is formed on one side of the upper section 16. Opposite the handle 22 there is provided a tapering spout 23 of substantially flattened V-shaped cross section. The spout 23 thus provides a V-shaped tapering pouring trough 24.

The lid 12 includes a disk 26 of substantially the same outer diameter of the upper end of the pitcher 11 and may be formed on its outer side with a circular recess 27. The recess 27 provides a convenient location for embossing or otherwise imprinting indicia relating to identifications, such as name of the user, room number or the like.

As shown the lid 12 is formed with a nose 28 shaped similarly to the upper end of the spout 23. Formed on the underside of the nose 28 is a groove 29 which provides a fluid passage over the wall of the spout 23.

Extending from and integral with the underside of the disc 26 is an annular depending flange 30 which is snugly accommodated within the open end 13 of the pitcher 11. Formed on the exterior wall of the flange 30 are a plurality of angularly spaced ribs 31 which serve to frictionally engage the interior wall about the open end 13 and thereby retain the lid 11 frictionally held within the opening while permitting relative rotation and removal. The ribs 31 are spaced to span the nose 28.

An open ended slot 32 is formed in the flange 30 in alignment with the groove 29 on the underside of the nose 28. It is to be noted however, that the upper end of the slot 32 terminates below the underside of the disk so that portion 33 of the flange 30 remains in engagement with the inner wall of the pitcher when the nose 28 is rotated out of alignment with the spout 23.

To discharge liquid contents from the carafe 10, the nose 28 is aligned with the spout 23. In this position the open ended slot 32 and groove 29 are aligned with the spout trough 24 as shown in FIGS. 2 and 5 so that the liquid contents are free to be discharged over the spout nose through the groove 29. It is to be noted that the open-ended slot 32 provides substantially a direct passage from the top of the pitcher 11 so that the carafe may be filled to its capacity while permitting easy initial pouring of the contents. At the same time, the passage defined by groove 29 over the end of the spout is somewhat restricted so that passage 29 serves in the nature of a strainer and prevents large objects such as ice or other solid contents from being discharged.

To substantially close or seal the carafe for normal pouring positions thereof the lid 12 is angularly rotated so that the nose 28 is out of alignment with the spout 23 at relative positions where the groove 29 is not in fluid communication with the top level of the liquid as the carafe is tipped. In these positions the flange portion 33 above the open ended slot 32 is seated against the inner wall so that no liquid is free to flow through the groove 29 over the top end of the particular angular position of nose 28 for sealing the carafe in normal tipped pouring positions is obviously dependent on the amount of liquid within the container.

While I have illustrated and described the preferred embodiment of my invention, it is to be understood that I do not limit myself to the precise construction herein disclosed and that various changes and modifications may be made within the scope of the invention as defined in the appended claims.

What I claim is:

1. A carafe comprising a one-piece molded body of generally circular cross sections and made from an expanded

foam polystyrene, said body having an open end, a pouring spout formed in said body and terminating at said upper end, a lid including a disk of substantially the same diameter as said upper end of said body and turnably seated in said open end, said disk including a nose adapted to overlie said pouring spout, a groove formed on the underside of said nose and providing a fluid discharge passage through said pouring spout when said nose is aligned therewith and being closed off from communication with said pouring spout when said nose is angularly displaced from alignment with said pouring spout thereby to seal said carafe, said disk includes a downwardly depending angular flange which is snugly received within said opening, said annular flange is formed with an open-ended slot aligned with said groove in said nose, said open-ended slot being vertically spaced from said groove so that a portion of 15 said annular flange depends into said body.

2. The invention as defined in claim 1 wherein said body includes an upper section and a lower section, said upper and lower sections being of different diameters at the juncture thereof to provide an interior stacking rim and an exterior stacking rim.

3. The invention as defined in claim 2, wherein the exterior of the upper section and lower section of said body is formed respectively with a plurality of horizontal bands, said bands gradually decreasing in diameter from the top to the bottom of 10 said body.

4. The invention as defined in claim 2, wherein a handle is formed integral with said upper section, said handle being of substantially T-shaped cross section and said stem of said T extends radially from said body.
